UNITED STATES PATENT OFFICE.

HERBERT H. FREEMAN, OF PIERRE, SOUTH DAKOTA.

ROTARY STEAM-ENGINE.

SPECIFICATION forming part of Letters Patent No. 609,579, dated August 23, 1898.

Application filed July 1, 1897. Serial No. 643,181. (No model.)

To all whom it may concern:

Be it known that I, HERBERT H. FREEMAN, a citizen of the United States, residing at Pierre, in the county of Hughes and State of 5 South Dakota, have invented certain new and useful Improvements in Reversible Rotary Steam-Engines; and I do declare the following to be a full, clear, and exact description of the invention, such as will enable others 10 skilled in the art to which it appertains to make and use the same.

My invention has relation to reversible rotary steam-engines; and the object is to provide a simple, effective, and economical engine of this class.

To this end the novelty consists in the construction, combination, and arrangement of the same, as will be hereinafter more fully described, and particularly pointed out in the 20 claims.

In the accompanying drawings the same reference characters indicate the same parts of the invention.

Figure 1 is a side elevation of a locomotive 25 fitted with my improved rotary engine. Fig. 2 is an end view of the cylinder detached from the locomotive. Fig. 3 is a front elevation of the rotating drum removed from the cylinder. Fig. 4 is a longitudinal section of 30 the same. Fig. 5 is an enlarged sectional detail of the valve-gear. Fig. 6 is an enlarged rear elevation of the cylinder. Fig. 7 is a detail view of the valve-gear rock-shaft. Fig. 8 is a detail plan of the back-pressure plate. Fig. 9 is an edge view of the same. Fig. 10 35 represents the packing-strip detached from the plate. Fig. 11 is a reduced front elevation of the cylinder, showing the exhaust steam chest. Fig. 12 is three detail views of 40 the drum packing-rings, and Fig. 13 shows a plan and an edge view of the guide-bar 52.

1 represents the locomotive, and 2 the transverse cylinder fixed under the forward end of the boiler.

45 3 represents the live-steam pipe, which connects the steam-dome on the boiler with the cylinder 2.

4 represents the exhaust-pipe, and 5 the exhaust-steam chest.

50 6 represents the live-steam chest; 7, the movable valve-seat, and 8 the slide-valve.

9 represents the back-pressure plate, which has a reciprocating movement in a radial guideway 10, formed in the cylinder-casing.

12 represents the rotating drum, fixed upon 55 the driving-shaft 13, journaled in the bearings 14, mounted in the frame 15, and provided with the cranks 16 16, arranged at a right angle to each other.

From the respective crank-pins the usual 60 connecting-rods extend to the driving-wheels.

The rotating drum is formed with two oppositely-disposed grooves 17 and 18, extending about half-way around the periphery of the drum, the groove 17 lying parallel with the 65 solid portion of the drum between the ends of the groove 18, and vice versa, as shown in Figs. 3 and 4.

The inner curved edge 20 of the back-pressure plate 9 conforms to the shape of the 70 grooves 17 and 18, which it snugly fits, the curved edge and the parallel side edges of said plate being formed with a rectangular groove 21, which receives the packing-strip 22 to form a steam-tight joint between said plate 75 and the contiguous face of the groove.

It will be understood that there are two independent plates 9, one for each groove, and also two slide-valves and sliding valve-seats, a 80 complete set of each being employed for each groove in the periphery of the drum.

Each valve is provided with a stem 23, pivoted to a vertical crank 24 on a rock-shaft 25, having a depending crank 26, carrying a link-block 27, engaging the link 28, forming a 85 part of the usual link reversing-gear of an ordinary locomotive, the link being pivoted to the shorter arm of a bell-crank lever 29, provided with an operating-rod 30, extending back to the cab. Each movable valve-seat 7 is 90 provided with two steam-ports 31 and 32, so arranged with reference to the stationary valve-seat 33 as to alternately close or open the live-steam ports 34 and 35, the port 34 opening into the cylinder 2 above the back-pressure plate 9 and driving the rotating drum 12 ahead, and the port 35 opening into the cylinder below the plate 9 to reverse the motion of 95 said drum to drive the locomotive backward, as will be hereinafter explained.

The sliding valve-seat 7 is provided with a stem 36, which is pivoted to a vertical lever

37, the upper end of which is pivoted to a rod 38, extending back to the cab. A connecting-rod 39 extends from the lever 37 to a bell-crank lever 40, and from this bell-crank lever 5 a vertical rod 41 connects to an arm 42 on a rock-shaft 43, journaled in brackets 44 44 on the front of the cylinder, and the inner end of said rock-shaft is provided with a crank-arm 45, to which the rod 46 is pivoted and 10 which extends into the exhaust-steam chest 5 and is connected to the exhaust-valve 47.

The exhaust-valve 47 is a plane rectangular plate and is adapted to close or open either of the exhaust-ports 48 or 49 alternately, and 15 when the engine is hooked in forgoing ahead the sliding valve-seat 7 is in the position shown in Fig. 5, and the exhaust-valve 47 closes the port 48 and leaves a clear exhaust-passage through the port 49. When the sliding valve-seat 7 is moved to the opposite end of its stroke, the "go-ahead" port 34 is blanked or closed, and the "backing-up" port 35, is opened and at the same time the exhaust-valve 47 has been shifted by the same 25 means and it closes the exhaust-port 49 and opens the port 48.

The back-pressure plate 9 is provided with a valve-stem 50, which is pivoted to a vertical lever 51, fulcrumed in a depending V-shaped bracket secured to the frame, and 52 represents a guide-bar pivoted at its rear end to said lever, its forward end extending through a guide-bracket 53, and its intermediate end is provided with a lateral cylindrical stud 54, which projects into an irregular endless guide-groove 55, formed in the flush end of the drum 12, and which serves to give the proper movement to the back-pressure plate to project it into and withdraw it from 40 the groove in the drum. A similar guide-groove is formed on the opposite parallel end of the drum to give a corresponding movement to the duplicate back-pressure plate.

Referring to Figs. 3 and 4, 56 56 represent 45 circumferential grooves, which receive the usual packing-rings. 57 57 represent transverse grooves extending across the solid face of the drum at each end of the grooves 17 and 18.

50 Referring to Fig. 12, 58 58 represent the packing-rings, formed with the usual lap-joint 59, which are arranged opposite to each other on their respective rings, and each ring 58 is provided with one or more integral lugs 60, 55 which project into a corresponding recess 61 in the bottom of the grooves 56 to prevent the rings slipping in said grooves when the engine is in action.

While I have described my improved reversible rotary steam-engine as applied to a locomotive, it will of course be understood that it is equally adapted for use as a stationary engine for electric-light service as well as marine use, and when mounted longitudi-

nally on a suitable truck it is particularly 65 adapted for use as a rotary snow-plow.

Although I have specifically described the construction and relative arrangement of the several elements of my invention, I do not desire to be confined to the same, as such 70 changes or modifications may be made as clearly fall within the scope of my invention without departing from the spirit thereof.

Having thus fully described my invention, what I claim as new and useful, and desire to 75 secure by Letters Patent of the United States, is—

1. The rotary steam-engine, comprising the cylinder 2 open at both ends, the live-steam chest 6 and the exhaust-steam chest 5, in combination with the exhaust-valve 47, the drum 12 mounted in said cylinder, and provided with the oppositely-disposed grooves 17 and 18 and the endless guide-grooves 55, the pressure-plates 9, 9, extending into the grooves 80 17 and 18 midway between the passages connecting the live-steam chest and the cylinder, the movable valve-seats 7, the slide-valves 8 and the guide-bars 52, 52, provided at one end with the stud 54 projecting into the guide-grooves 55, said bars being operatively connected at their opposite ends to said slide-valves, substantially as shown and described. 90

2. The rotary steam-engine comprising the cylinder 2, open at both ends, the live-steam chest 6 and the exhaust-steam chest 5, arranged on opposite sides of said cylinder, the drum-piston 12 mounted in said cylinder and having its solid ends arranged in the same plane with the ends of the cylinder so as to 100 form closed heads for said cylinder, the steam-inlet valves 8, 8, operatively connected to said drum-piston, and the exhaust-valve 47, adapted to be operated by hand and independently of said steam-inlet valves, substantially as 105 and for the purpose set forth.

3. The rotary steam-engine, comprising the cylinder 2, open at both ends, the live-steam chest 6 and the exhaust-steam chest 5, arranged on opposite sides of said cylinder, the 110 drum-piston 12, adapted to fill said cylinder and form heads therefor, and formed with the oppositely-arranged grooves 17 and 18 in combination with the pressure-plates 9, 9 projecting into said grooves, the movable valve-seats 115 7 and the steam-inlet valves 8 mounted in said live-steam chest 6, and means for independently operating said valve-seats and valves and the exhaust-valve 47, and means for manually operating said exhaust-valve independently of said inlet-valves, substantially as 120 shown and described.

In testimony whereof I hereunto affix my signature in presence of two witnesses.

HERBERT H. FREEMAN.
